LACING HOOK FOR SHOES OR SIMILAR ARTICLES

Walter A. Maring, Huntington Park, Calif.

Application April 23, 1951, Serial No. 14,916

Term of patent 3½ years

(Cl. D17—12)

To all whom it may concern:

Be it known that I, Walter A. Maring, a citizen of the United States, residing at Huntington Park, in the county of Los Angeles, State of California, have invented a new, original, and ornamental Design for a Lacing Hook for Shoes or Similar Articles, of which the following is a specification, reference being had to the accompanying drawing, forming a part thereof.

Fig. 1 is a front elevational view of a lacing hook for shoes or similar articles, showing my new design;

Fig. 2 is a side elevational view thereof.

Figs. 3 and 4 are top and bottom edge views, respectively, of the lacing hook as shown in Fig. 1.

I claim:

The ornamental design for a lacing hook for shoes or similar articles, as shown.

WALTER A. MARING.
